UNITED STATES PATENT OFFICE

CHARLES H. HODGES, OF DETROIT, MICHIGAN, ASSIGNOR TO THE DETROIT STEAM RADIATOR COMPANY, OF SAME PLACE.

DESIGN FOR A RADIATOR.

SPECIFICATION forming part of Design No. 18,312, dated May 15, 1888.

Application filed June 10, 1887. Serial No. 240,952. Term of patent 7 years.

To all whom it may concern:

Be it known that I, CHARLES H. HODGES, a citizen of the United States, residing at Detroit, in the county of Wayne and State of Michigan, have invented and produced a new and original Design for Radiators, of which the following is a specification, reference being had to the accompanying drawings, forming part thereof.

10 In the drawings, Figure 1 is a view in elevation of a single pipe or loop radiator illustrating my design, and Fig. 2 is a perspective view of a multiple-loop radiator having the same ornamental design.

15 My design consists in a radiator having a section of ornamental leaves at the top of each vertical radiator pipe or loop and a section of ornamental leaves between the bottom and top of each loop.

A designates the top section of ornamental leaves, and B the section of ornamental leaves between the bottom and top of a single pipe or loop radiator, while A' and B' designate the corresponding ornamental features of the multiple-loop radiator. 25

What I claim is—

The design for a radiator, which consists in a section of ornamental leaves at the top of each radiator pipe or loop and a section of ornamental leaves between the bottom and top of each vertical loop, as herein shown and described. 30

In testimony whereof I sign this specification in the presence of two witnesses.

CHARLES H. HODGES.
